UNITED STATES PATENT OFFICE.

JOHN L. PAINTER, OF BELLEVUE, OHIO.

FOOT-POWER HAMMER.

SPECIFICATION forming part of Letters Patent No. 292,342, dated January 22, 1884.

Application filed August 3, 1883. (Model.)

To all whom it may concern:

Be it known that I, JOHN L. PAINTER, of Bellevue, Huron county, Ohio, have invented a new and Improved Foot-Power Hammer, of which the following is a full, clear, and exact description.

The object of the invention is to improve foot-power hammers, as hereinafter described, and pointed out in the claims.

10 Reference is to be had to the accompanying drawings, forming part of this specification, in which similar letters of reference indicate corresponding parts in both figures.

Figure 1 is a side elevation of my improved 15 foot-power hammer, with some parts in section; and Fig. 2 is a plan view.

The hammer-staff *a* is pivoted at *b* to the head of a vertical shaft, *c*, that is fitted in the socket *d* of the top of the stand *e*, so as to rise 20 and fall and to turn freely; and the lower end of the shaft has a step in the lever *f*, pivoted to the hind leg of the stand at *g*, and ranging forward and alongside of the anvil-block *h*, when its free end is to be used by the operator for raising and lowering the hammer, as 25 the work may demand, by swinging said lever up and down. A bar, *i*, having a series of holes, *j*, is attached to the stand *e*, and arranged in a slot, *k*, through said lever *f*, for 30 fastening the lever at any point along it by a pin, *l*, to set the hammer at the required height. An arm, *m*, is attached to the lower end of shaft *c* over lever *f*, which arm is connected by rod *n* to a lever, *o*, pivoted on lever 35 *f* at *p*, near the anvil-block, where the operator may readily reach said lever to work it for turning the shaft to swing the hammer along the face of the anvil, the lever *f* having a plate, *f'*, with a series of notches or holes, *f''*, 40 in any one of which a catch-pin, *f'''*, may be set after passing through lever *o*, to lock the hammer in any desired position to which it may be swung. The hammer-staff *a* is connected to the foot-lever *q*, that is employed 45 for working said hammer, by the cord, chain, or strap *s*, which passes through a slot, *t*, in the hammer-staff, and connects by a ring, *u*, with a rod, *v*, on which a coiled spring, *w*, is fitted to be contracted, when the hammer is 50 forced down, for raising said hammer again. The spring *w* bears against the head *x* of the

shaft *c* for its base, and the rod *v* connects with the free end of the spring by an adjusting-nut, *y*, and washer *z*, which also serve to regulate the tension of the spring for setting it properly for raising up the hammer promptly. The shaft *c* has a vertical extension, *a'*, above the head, about half the length of the hammer-staff, and suitably curved backward from said staff to support a coiled buffer-spring, *b'*, that arrests the hammer at the end of the up-stroke without shock or jar of any considerable extent, and I make the hammer-staff *a* adjustable forward and backward with relation to the anvil by placing the pivot *b* of the staff in slots *e'* of the arms *x'* of head *x*, and I provide a thumb or hand screw, *d'*, on pivot *b*, for quickly clamping the pivot in the slots at any desired position.

I do not abandon or dedicate to the public 70 any patentable feature set forth herein and not hereinafter claimed, but reserve the right to claim the same either in a reissue of any patent that may be granted upon this application or in other applications for Letters 75 Patent that I may make.

Having thus described my invention, I claim as new and desire to secure by Letters Patent—

1. The combination, with the hammer-staff *a*, having pivot *b*, of a hammer-shaft, *c*, carrying a head, *x*, provided with horizontally-slotted arms *x'*, and hand-screw *d'*, whereby the hammer-shaft may be brought forward more or less, as described.

2. The combination of the hammer-shaft *c* 85 with the lever *f*, provided with a step for said hammer-shaft, and pivoted at its rear end to stand *e*, and a perforated arm, *i*, passing through said lever in front of its step, and a connecting-pin, *l*, whereby the hammer-shaft 90 may be adjusted vertically, substantially as set forth.

3. In a foot-power-hammer mechanism for vertically and horizontally adjusting the hammer-shaft, consisting of a lever, *f*, pivoted to 95 the rear under side of the frame, and provided with a step for the hammer-shaft *c*, and having at its forward end a pivoted adjustable lever, *o*, to which is pivoted a connecting-rod, *n*, extending rearward, and pivoted 100 to an arm, *m*, rigidly secured to the lower part of the hammer-shaft above its step, a perfo-

rated arm passing through said lever *f*, and a pin, *l*, substantially as set forth.

4. The combination, with the hammer-shaft *c*, having arm *m*, of the connecting-rod *n*, lever *o*, pin *f*³, and plate *f'*, having holes *f*², whereby the hammer may be adjusted in the arc of a circle, as described.

5. The combination of the treadle *g*, strap *s*, hammer-staff having slot *t*, the rod *r*, the shaft

c, having slotted extension *c'*, and the spring *10*, and the lever *w*, whereby the hammer may be actuated on its downward and upward movement, as described.

JOHN L. PAINTER.
